RAILWAY TRACK CIRCUIT APPARATUS

Robert Mills, Kew Gardens, N. Y., assignor to The Union Switch & Signal Company, Swissvale, Pa., a corporation of Pennsylvania

Application April 12, 1939, Serial No. 267,482

11 Claims. (Cl. 246—41)

My invention relates to railway track circuit apparatus, and has for an object the provision of novel and useful apparatus for improving the shunting sensitivity of the track circuit and for decreasing track circuit power. Other objects, features and advantages of my invention will appear as the description progresses.

I shall describe several forms of apparatus embodying my invention and shall then point out the novel features thereof in claims.

In the accompanying drawing, Fig. 1 is a diagrammatic view showing one form of track circuit apparatus embodying my invention in which polarized line circuits are employed for signal control. Fig. 2 is a diagrammatic view also embodying my invention and showing a modified form of a portion of Fig. 1 in which a neutral line circuit is employed. Fig. 3 is a diagrammatic view similar to Fig. 2, also embodying my invention and showing a normally deenergized auxiliary relay. Fig. 4 is a diagrammatic view showing my invention applied to a portion of single track.

In each of the several views, like reference characters designate similar parts.

In track circuits employing the usual form of primary-secondary track relay combination, the secondary relay operates directly on the primary or track relay by cutting out a certain number of turns from the relay winding when the section is unoccupied and inserting an equivalent resistor to replace the turns which have been rendered ineffective. This whole operation is usually performed at the relay end of the track circuit. Under certain conditions, however, it is advantageous to permit the secondary relay to perform its improved shunting operation at the battery or feed end of the track circuit, especially if approach lighted signals are employed which make available an auxiliary (approach lighting) relay at the signal location. This auxiliary relay may then be used to perform the additional function of improving the shunting sensitivity of the track circuit in a manner which will be clear from the description which follows. In the particular embodiments which I have shown, the improved shunting sensitivity is obtained by increasing the total resistance in series with the battery at the feed end of the track circuit. This method is particularly advantageous in connection with track circuits in which it is important to conserve the track battery output as much as possible.

Referring now to Fig. 1, the reference characters 1 and 1a designate the rails of a stretch of track in which traffic moves in the direction in-

icated by the arrow. The rails are divided by insulated rail joints 5 to form a series of blocks of which only the blocks 2—3 and 3—4 are shown complete in the drawing. Block 3—4 includes the two cut sections 3—3a and 3a—4. The track circuit for block 2—3 includes a track battery TB, current limiting resistors 7 and 6, the rails of the section, and the track relay 2TR. Each of the remaining track circuits includes corresponding apparatus designated by similar reference characters except for identifying numerals corresponding to the location. Traffic entering each block is controlled by a suitable signal S which, as here illustrated, is of the color light type capable of displaying a green, yellow, or red indication as demanded by traffic conditions in advance.

Each signal is governed by a line relay HDR, here shown as a polarized relay, which is controlled by its associated track relay TR and the line relay HDR at the signal next in advance. Looking at line relay 2HDR, the polarized line circuit for this relay is controlled by the track relay 2TR over its front contact 8 and pole changing contacts 9 and 10 of the line relay 3HDR next in advance. The line relays HDR are of the slow pick-up type and are so designed that their front contacts remain closed during a reversal of the polar contact structure. A relay which operates in this manner and is suitable for use herein is shown and described in Letters Patent of the United States No. 2,063,300 granted December 8, 1936 to Arthur E. Dodd, for Railway track circuit apparatus. This relay has a retaining winding controlled by a front contact 11 of the associated track relay to prevent release of its neutral armature during a reversal of the polar armature, but since the structure of this relay forms no part of my present invention no further description of this relay is necessary for an understanding of my invention.

It should be pointed out that if an HDR relay of the retained neutral armature type is not available, proper signal control and selection may be obtained by an HDR relay of the usual polarized type operating in conjunction with an additional slow acting repeater relay which pole changes the line circuit to the rear. This alternative combination of an HDR relay with a slow acting repeater represents well-known signaling practice and need not be described in detail as it also forms no part of my present invention.

At each signal location I have shown an auxiliary relay ER which is connected in series with the winding of the HDR relay next in the rear. Relay ER may be the usual approach lighting re-

lay which causes illumination of its associated signal only upon the approach of a train. When such relays are already available in the system, no additional relays are required for carrying out the purposes and objects of my invention. In accordance with my invention, the approach lighting relay is caused to perform, in addition to its approach lighting function, the function of a "secondary" relay of a "primary-secondary" track relay combination in that it operates to improve the shunting sensitivity and decrease the power consumption of its associated track circuit by introducing additional resistance in series with the battery when the section becomes unoccupied. This operation will be best understood by considering certain typical traffic conditions.

With no train occupying the blocks shown, or the two blocks immediately in advance of signal 4S, all of the track relays, line relays, and approach lighting relays are energized to the positions shown, whereby the circuit for lamp G of each signal is prepared, but the signal is dark because of the open circuit at back contact 12 of each relay ER. Under this condition, the short-circuit around resistor 7 in the track battery circuit is open at back contact 13 of each relay ER so that the track relay current is reduced, with a resulting increase in shunting sensitivity and saving in track power input. At the cut section location 3a, I have shown adjoining track feed apparatus for both of the track circuits 3-3a and 3a-4. This apparatus arrangement permits the auxiliary relay 3AER to control not only the resistor 7 of its associated track circuit, but also to control over its back contact 14 the corresponding resistor of the adjoining track circuit.

When a train enters block 2-3, the track relay 2TR will release and in so doing will open the line circuit which supplies operating current to relays 2HDR and 3ER so that both of these relays will also release. The closing of back contact 15 of relay 2HDR will illuminate the stop lamp R of signal 2S, and the closing of back contact 12 of relay 3ER will illuminate the proceed lamp G of signal 3S over obvious circuits, each of which starts at one terminal B of a suitable source of current (not shown) and ends at the other terminal C of the same source. At the same time, the closing of back contact 13 of relay 3ER will shunt the resistor 7 in order that the track relay 2TR may pick up readily when the train vacates the section.

When the train enters section 3-3a, the release of track relay 3TR will open the line circuit which energizes all three of the relays 3HDR, 3AER and 4ER so that all of these relays will release. As a result, the proceed lamp G of signal 4S will become lighted over back contact 12 of relay 4ER, and signal 3S will change its indication from proceed to stop due to the closing of back contact 15 of relay 3HDR. The release of relay 3HDR serves to pole-change the line circuit to the rear so that when relay 2TR subsequently picks up and closes the line circuit, relay 2HDR will be energized in the reverse direction from that shown, in order that the caution lamp Y of signal 2S may become lighted upon the approach of a following train. The release of relay 3AER will close a shunt for resistor 7 at back contact 13, thus preparing the track circuit for pick-up of relay 3TR when the train vacates the section. At the same time, resistor 7 of the forward cut section is short-circuited over back contact 14 of relay AER. This last

operation does not entail any undesired consequences because the line circuit is already open at front contact 8 of relay 3TR, so that relay 3ATR will have ample opportunity to release before the train finally clears the rear cut section 3-3a. When the train passes location 4, relay 4TR will release, opening the circuit for relay 4HDR and causing signal 4S to display its stop indication.

As soon as the train completely clears section 2-3, relay 2TR will pick up, thus completing a reverse energizing circuit for relay 2HDR whereupon polar contact 16 of this relay will swing to the right so that signal 2S will be conditioned to display a caution indication at lamp Y for a following train. Completion of the line circuit will pick up relay 3ER which will open back contact 13 to restore high shunting sensitivity and low power input to the track circuit of block 2-3. The opening of back contact 12 of relay 3ER also insures that once relay 3HDR picks up, signal 3S will become extinguished, provided a following train has not entered section 2-3.

When the train vacates section 3-3a, relay 3TR will pick up but nothing further will happen until the train completely clears section 3a-4 so that relay 3ATR will pick up. When this occurs, the line circuit for block 3-4 will be energized with current of reverse polarity and all of the relays 3HDR, 3AER and 4ER will become energized. The current in relay 3HDR will be of reverse polarity so that signal 3S will be conditioned for displaying a caution indication. The pick-up of relay 3AER will restore the sensitivity of both track circuits 3-3a and 3a-4. Also, the pick-up of relay 4ER will prepare the deenergization of signal 4S once the train clears the block in advance of location 4, provided no following train is approaching.

When the train finally clears the block in advance of location 4, relay 4HDR will become energized and all of the apparatus will then be restored to the condition in which it is illustrated in the drawing.

It will be apparent from the foregoing description of Fig. 1 that I have provided apparatus at the track feed end of the block operating in conjunction with the track relay for controlling the sensitivity of the track circuit and that this apparatus may be a part of the approach lighting or other approach control apparatus associated with the track circuit.

Referring to Fig. 2, this figure shows a single track circuit corresponding, for example, to block 2-3 of Fig. 1 but employing a non-polarized or neutral line circuit suitable for two-position signaling. Relay HDR may, in this modification, be an ordinary slow pick-up neutral relay controlled over the line circuit in series with relay ER, as in Fig. 1. When the section is occupied, relays TR, HDR and ER will all be released and resistor 7 will be short-circuited over back contact 13 of relay ER. Contact 25 may control suitable signaling apparatus, as in Fig. 1. When the section is vacated, these relays will be picked up and the opening of back contact 13 of relay ER will restore the high shunting sensitivity and low power input to the track circuit. Additional control by advance traffic for the line circuit of Fig. 2 may be provided, if desired, but is not essential for the practice of my invention. One form of such additional control is shown, for example, in block 3-4 of Fig. 1.

Referring to Fig. 3, this figure differs from Figs. 1 and 2 chiefly in that I have provided a

normally deenergized relay ER. This arrangement is somewhat safer in that a broken wire or other failure of the relay ER to pick up results in a decrease rather than an increase of energy in the track circuit. The line circuit in this case does not include the winding of relay HDR which relay is energized locally, in the usual manner. An adjustable resistor 17 is included in the line circuit in order to adjust the current in this 10 circuit with respect to the pick-up and release values of relay ER so as to obtain sensitive operation. When a train occupies the section, relay ER will be picked up over a circuit which includes one terminal of battery TB, the upper rail, wires 15 20 and 21, back contact 19 of relay TR, the line wire 22, resistor 17, and winding of relay ER, to the other terminal of battery TB. Since relay ER is now picked up, its front contact 18 is closed, thus shunting out resistor 7 under the 20 occupied condition as in the two previous figures. Contact 26 may control signaling apparatus, as before. When the train leaves the section, relay TR will pick up, opening back contact 19 to deenergize the line circuit so as to release ER 25 and restore the unshunted condition of resistor 1.

Referring to Fig. 4, this figure shows my invention applied to a portion of single track in which traffic may move in either direction. In this figure, the winding of relay ER is included in 30 the line circuit for the HDR relay as in Fig. 1, and the operation of the apparatus as a whole will be clear from the description presented in connection with Fig. 1. It will be noted that the resistor 7 for each track circuit is shunted by 35 back contacts 13 and 14 in series of the two ER relays, both of these relays being released due to the opening of front contacts 23 and 24 of the TR relay when a train enters the section from either end. The complete control of the east- 40 bound and westbound line circuits is not shown as this control is well known and forms no part of my invention. It will be apparent that I have provided in Fig. 4 a simple and compact arrangement of apparatus for improving the shunting sensitivity and decreasing the power input of 45 track circuits for single track, two-direction signaling.

Although I have herein shown and described only a few forms of railway track circuit apparatus embodying my invention, it is understood 50 that various changes and modifications may be made therein within the scope of the appended claims without departing from the spirit and scope of my invention.

55 Having thus described my invention, what I claim is:

1. In combination with a section of railway track, a track relay receiving current from the rails at one end of said section, a source of track 60 circuit current at the other end of said section, a current limiting device at said other end of the section for limiting the current supplied to the rails from said source, an auxiliary relay at said other end of the section, a line circuit for 65 energizing said auxiliary relay including a contact of said track relay, means including a contact of said auxiliary relay effective when said section is unoccupied for increasing the effective value of said current limiting device to thereby 70 increase the shunting sensitivity of said track section and decrease the power input thereto, and approach control means governed by said auxiliary relay, whereby said auxiliary relay combines the functions of an approach relay and a 75 secondary relay.

2. In combination with a section of railway track, a track relay receiving current from the rails at one end of said section, a source of track circuit current at the other end of said section, a current limiting device at said other end of the section for limiting the current supplied to the rails from said source, an auxiliary relay at said other end of the section, a line circuit governed by said track relay for controlling the operation of said auxiliary relay, means controlled by said auxiliary relay for at times increasing the effectiveness of said current limiting device to thereby increase the shunting sensitivity of said track section and decrease the power input thereto, and approach control means governed by said auxiliary relay, whereby said auxiliary relay combines the functions of an approach relay and a secondary relay.

3. In combination with a section of railway track, a track relay receiving current from the rails at one end of said section, a source of track circuit current at the other end of said section, a current limiting device at said other end of the section for limiting the current supplied to the rails from said source, an auxiliary relay at said other end of the section, a line circuit for energizing said auxiliary relay including a front contact of said track relay, means including a back contact of said auxiliary relay for decreasing the effectiveness of said current limiting device when said section is occupied, and approach control means governed by a second back contact of said auxiliary relay, whereby said auxiliary relay combines the functions of an approach relay and a secondary relay.

4. In combination with a section of railway track, a track relay receiving current from the rails at one end of said section, a source of track circuit current at the other end of said section, a current limiting device at said other end of the section for limiting the current supplied to the rails from said source, an auxiliary relay at said other end of the section, a line circuit for energizing said auxiliary relay including a back contact of said track relay, means including a front contact of said auxiliary relay for decreasing the effectiveness of said current limiting device when said section is occupied, and approach control means governed by said auxiliary relay, whereby said auxiliary relay combines the functions of an approach relay and a secondary relay.

5. In combination with a section of railway track, a track relay receiving current from the rails at one end of said section, a source of track circuit current at the other end of said section, a current limiting device at said other end of the section for limiting the current supplied to the rails from said source, an auxiliary relay at said other end of the section, a circuit controlled by said track relay for energizing said auxiliary relay from said source over a line wire and a rail of said section, and means controlled by said auxiliary relay for decreasing the effectiveness of said current limiting device when said section is occupied.

6. In combination, two adjoining sections of railway track having their feed ends at the junction of said two sections, a track relay for each section, a source of current for each section located at the respective feed end thereof, a current limiting device for each of said sources for limiting the current supplied thereby to the respective track section, an auxiliary relay associated with said sources at the track feed location

for said two sections, a line circuit for energizing said auxiliary relay including a contact of the track relay for each of said two sections, and means governed by said auxiliary relay for controlling the effective value of each of said current limiting devices, whereby said one auxiliary relay performs the functions of a secondary relay for both said track relays.

7. In combination, two adjoining sections of railway track having their feed ends at the junction of said two sections, a track relay for each section, a source of current for each section located at the respective feed end thereof, a current limiting device for each of said sources for limiting the current supplied thereby to the respective track section, an auxiliary relay associated with said sources at the track feed location for said two sections, a line circuit for energizing said auxiliary relay including a front contact of the track relay for each of said two sections, and means including back contacts of said auxiliary relay for controlling the effective value of each of said current limiting devices, whereby said one auxiliary relay performs the functions of a secondary relay for both said track relays.

8. In combination with a stretch of single track railway in which traffic may move in either direction over the stretch, two track circuit sections for said stretch having their feed ends adjoined, a track relay for each section, a source of current for each section located at the respective feed end thereof, a current limiting device for each of said sources for limiting the current supplied thereby to the respective track section, an auxiliary relay for each of said sources located at the feed end of its respective track circuit, a line circuit for each auxiliary relay controlled by both said track relays, and means governed jointly by said auxiliary relays for controlling the effective value of each of said current limiting devices.

9. In combination with a section of railway track, a track relay receiving current from the rails at one end of said section, a source of track circuit current at the other end of said section, a current limiting device at said other end of the section for limiting the current supplied to the rails from said source, an approach control relay at said other end of the section, a

line circuit for said approach control relay governed by said track relay, signaling apparatus governed by said approach control relay, and means also governed by said approach control relay for decreasing the effectiveness of said current limiting device when said section is occupied, whereby said approach control relay combines the functions of an approach relay and a secondary relay.

10. In combination with a section of railway track, a track relay receiving current from the rails at one end of said section, a source of track circuit current at the other end of said section, a current limiting device at said other end of the section for limiting the current supplied to the rails from said source, a line relay at said one end of the section, an approach control relay at said other end of the section, a line circuit controlled by said track relay for energizing both said line relay and said approach control relay, a signal for said section controlled by said line relay, signaling apparatus for the section next in advance of said section controlled by said approach control relay, and means also controlled by said approach control relay for decreasing the effectiveness of said current limiting device when said section is occupied, whereby said approach control relay combines the functions of an approach relay and a secondary relay.

11. In combination with a section of railway track, a track relay receiving current from the rails at one end of said section, a source of track circuit current at the other end of said section, a current limiting device at said other end of the section for limiting the current supplied to the rails from said source, a signal control line relay at said one end of the section, an approach control relay at said other end of the section, a line circuit controlled by said track relay for energizing both said line relay and said approach control relay in series, signaling apparatus controlled by said approach control relay, and means also controlled by said approach control relay for decreasing the effectiveness of said current limiting device when said section is occupied, whereby said approach control relay combines the functions of an approach relay and a secondary relay.

ROBERT MILLS.
